UNITED STATES PATENT OFFICE.

JOHN H. JEFFRIES AND EDWARD M. DOHERTY, OF LOS ANGELES, CALIFORNIA.

PUMP PLUNGER.

Application filed June 7, 1926. Serial No. 114,054.

This invention relates to pump plungers, and more especially to that type of plunger having a cup of flexible material adapted to engage the inner face of the pump cylinder 5 in order to prevent leakage between the plunger and said cylinder.

In pumps heretofore constructed and provided with plunger cups, the construction of the plunger is such that the pressure of the fluid being pumped, upon inward stroke of the plunger, forces the flexible cup between the plunger and the cylinder, thus causing the cup to buckle, and the buckling causes the rim of the cup to be contracted. Obviously, contraction of the rim permits sand and other foreign substances to deposit between the cup and cylinder wall, producing excessive wear on the cylinder and cup.

An object of this invention is to avoid the foregoing difficulty and to insure relatively long life of the cup.

Another object of this invention is to provide a construction that will support the cup in such manner that it cannot be forced between the plunger and wall of the cylinder.

Other objects and advantages will appear in the subjoined detailed description.

The accompanying drawings illustrate the invention.

Figure 1 is a sectional view of a plunger constructed in accordance with the provisions of this invention, a cylinder being indicated in broken lines.

Figure 2 is a cross section of the plunger on the line indicated by 2-2, Figure 1.

Figure 3 is a view looking at the lower end of Figure 1.

The plunger body may be of any suitable construction and, in this instance, the construction is as follows: There is provided a tubular stem 4 having thereon an enlarged portion 5, which is provided with an internal shoulder 6 seating against an internal shoulder 7 on the stem 4. The shoulders 6, 7 are held in engagement by a tubular nut 8 that is threaded in one end of the member 5, against one end of the stem 4. A sleeve 9 fits tightly upon the stem 4, and mounted to shift on said sleeve is a valve 10 adapted to engage a recessed seat 11 in one end of the member 5. The construction of the valve 10 and the resilient means for urging said valve toward its seat need not be described in detail herein as the same have been fully described in our Patent No. 1,491,044, dated April 22, 1924.

The member 5 is provided with a portion

12 of reduced outside diameter terminated at one end by an external shoulder 13 on the member 5. The portion 12 is provided at its other end with a cup seat 14, screw threaded onto said portion 12, and between the shoulder 13 and said cup seat is any desired number of packing cups 15. In this particular instance, three such cups are shown but it is to be understood that one or more may be employed, according to the desire of the constructor. The cups 15 are simply cup-shaped members of leather or other suitable flexible packing material provided with a central opening 16 through which the reduced diameter portion 12 extends. When a plurality of seats 15 is employed, it is necessary to provide other cup seats 17, each of which has a portion 18 of reduced outside diameter extending inside of the adjacent cup 15 and an enlarged portion 19 forming a seat for one of the cups

The member 14 and the enlargements 19 are provided with recesses 20, the outer wall portions of which have their inner faces curved outwardly and upwardly, as indicated at 21 and the rim of each recess 20 extends at least to the level of the lower end of the member 18 that engages the cup 15 fitting in said recess. It is even preferable to extend the rim of the recess somewhat above the level of the lower end of the adjacent member 18. The recess 20 is greater in depth than the thickness of the cup and as shown in the drawings the mouth of this recess is of substantially less diameter than the outside diameter of the cup seat, the wall of the recess adjacent to the mouth thereof being normal to the horizontal plane in which the upper extremity of said seat lies. By this construction, fluid pressure against the lower portion of the inside of the packing cups cannot force the cups between the plunger and the cylinder wall indicated at A. When the cup holding recesses are shallow, as ordinarily constructed, or, in other words, constructed so that the recess rims are below the level of the lower end of the spacing member, the material of which the cup is made is bent by the fluid pressure and crowded between the plunger and cylinder wall, thus producing buckling of the cylindrical wall of the packing cup and the buckling results in contraction of the rim of the cup away from the cylinder wall, thus permitting sand to enter between the packing cup and cylinder wall, resulting in scoring of the cylinder within a short period of time after the plunger starts to operate.

The construction just described may be fur-

- ther described as follows: The depth of each recess 20 is as great as the thickness of the cup 15 and, in the instance shown, the depth of each recess is considerably greater than the thickness of the cup. When the cup containing recesses are constructed as described, the fluid pressure within the lower portions of the cups cannot force the lower portions of the cups between the cup supporting members 14 or 17, 5 as the case may be, because said cups are backed externally by metal to a point above where such pressure can become effective to bend the cup outwardly between the members 14 or 17 and the cylinder wall. However, the 10 fluid pressure within the upper portion of the cups is effective to hold the rim portion of the cups in close contact with the inner face of the cylinder, thus to prevent sand from lodging between the cups and the cylinder wall. 15 20 Inasmuch as the members 14, 17 perform the same function of externally backing up the cups 15 with a rigid wall, the term "cup seat" is applied herein to each of said members and said term will be employed in the appended 25 claims.

It will be seen that the uppermost cup 15 is held between the shoulder 13 and the adjacent member 17 and that the lower ends of the members 17 constitute shoulders 22 between 30 which and the next lower seat, the cup 15 is clamped.

The invention operates as follows: When the plunger moves on its down stroke, the fluid being pumped presses against the under face 35 of the valve 10, causing said valve to open so that the fluid will pass into the space above the plunger. Upon reversal of the plunger, the fluid pressure above the valve 10 will hold said valve closed and fluid pressure within the 40 cups 15 will hold the rims of said cups in close

contact with the cylinder, thus avoiding leakage of fluid above the plunger past the cups to the space beneath the plunger where a partial vacuum is tended to be produced upon the up stroke of the plunger. On the down stroke 45 of the plunger, the projecting portion of the cup will be relieved from the pressure bending to press it against the working barrel and will be free from contact therewith, due to the construction of the seat, so that frictional wear is 50 reduced and the life of the cup materially lengthened as the result thereof.

From the foregoing, it will be readily understood that the invention, though apparently of a simple nature, is very effective in preventing leakage and affording long life to the plunger cups the construction preventing buckling of the cups, wedging of the cups between the plunger and cylinder, or contraction 55 of the rims of the cups.

We claim:

A pump plunger comprising a cylindrical body provided with an annular shoulder, a cup seat surrounding the body and provided with a recess, the outer wall of the recess being curved outwardly and upwardly, and a flexible packing cup fitting the recess and shoulder, the depth of the recess being greater than the thickness of the cup, the wall of the recess adjacent to the mouth thereof being normal to the horizontal plane in which the upper extremity of said seat lies, and the mouth of the recess being of substantially less diameter than the outside diameter of the cup seat.

Signed at Los Angeles, California, this 21st 75 day of May, 1926.

EDWARD M. DOHERTY.
